US0D1110969S

(12) **United States Design Patent** (10) **Patent No.:** **US D1,110,969 S**
(45) **Date of Patent:** **** Feb. 3, 2026**

(54) **CONTROL DEVICE**

(71) Applicant: **Lutron Technology Company LLC**,
Coopersburg, PA (US)

(72) Inventors: **Gregory Altonen**, Easton, PA (US);
Susan Hakkarainen, Doylestown, PA (US); **Jason C. Killo**, Emmaus, PA (US); **Brad Michael Kreschollek**, Bethlehem, PA (US); **Noel Mayo**, Philadelphia, PA (US); **Matthew Philip McDonald**, Phoenixville, PA (US)

(73) Assignee: **Lutron Technology Company LLC**,
Coopersburg, PA (US)

(**) Term: **15 Years**

(21) Appl. No.: **29/986,041**

(22) Filed: **Jan. 17, 2025**

CLAIM

The ornamental design for a control device as shown and described.

DESCRIPTION

FIG. 1 is a front perspective view of a control device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the control device which form no part of the claimed design.

1 Claim, 4 Drawing Sheets

Related U.S. Application Data

continuation of application No. 29/594,200, filed on Feb. 16, 2017, now Pat. No. Des. 837,168.
